UNITED STATES PATENT OFFICE.

JOHN EMIL LILJEBLAD, OF CHICAGO, ILLINOIS.

BURGLAR-ALARM.

1,054,971.

Specification of Letters Patent.

Patented Mar. 4, 1913.

Application filed October 22, 1909. Serial No. 524,036.

To all whom it may concern:

Be it known that I, JOHN EMIL LILJEBLAD, a citizen of the United States, and resident of Chicago, in the county of Cook and State of Illinois, have invented a certain new and useful Improvement in Burglar-Alarms, of which the following is a description, reference being had to the accompanying drawings, which form a part 10 of my specification.

My invention relates to an improvement in burglar alarms of the type wherein a line or wire is secured across or adjacent to places of ingress to a building or room; the 15 free end of said line or wire being held in place in any convenient manner, while the other end is secured to mechanism which is held preferably under tension and adapted to cause an electrical circuit to be formed 20 the moment the line or wire is interfered with, thereby sounding the alarm.

In the drawings:—Figure 1 is a perspective view of the alarm mechanism incased in a small box with the lid shown open and 25 partly broken away and the alarm “set”. Fig. 2 is a detail view in elevation of the casing of the mechanism whereby the alarm is controlled, looking at the side of the casing where the electrodes are brought into 30 contact. Fig. 3 is a detail view in elevation of said mechanism, looking at the open side of the casing wherein the operating-mechanism is mounted. Fig. 4 is a longitudinal sectional view on the line 4—4 of Fig. 3. Fig. 5 illustrates my invention applied to 35 a transom, with tripping mechanism secured onto a door whereby the movement of either the transom or door will “set off” the alarm. Fig. 6 is a side view of the tripping mechanism shown in Fig. 5 with a portion 40 of the door-casing shown in section. Fig. 7 is a detail view partially in section and taken on the line 7—7 of Fig. 6 and looking in the direction of the arrows, illustrating the means employed whereby the 45 tripping mechanism may be placed into position to engage or trip the means for releasing the electrical contacts or electrodes whereby the circuit is controlled and the 50 alarm mechanism actuated. Fig. 8 is a detail view of the combination or means shown in Fig. 7, illustrating that portion whereby the position of the tripping-mechanism is determined.

To illustrate the principle of my invention, I have shown the alarm “set” in Fig.

5, by leading the line *a*—which may be either a string or wire or other suitable device—across the lower part of the transom *A* with its free end secured at *b*. This line *a* leads 60 to the alarm-circuit controlling mechanism which, together with the alarm may for convenience be inclosed in a box *B*. The alarm comprises the ordinary style of electric-bell *C*; the current being supplied by a 65 suitable battery *D*, which is wired to the electro-magnet of the bell *C* by wire *c*, and also to plug *d* by wire *c'*,—see Fig. 1—and the circuit is completed through switch *e* when the latter is moved into contact with 70 plug *f*, through wire *g* connected with contact-piece or electrode *h*, electrode *i*, through the metallic casing or wall *E* and wire *j* to the other plug of the bell. As the bell is of 75 a well-known type it will not be necessary 80 to follow out the manner in which the current passes through the electro-magnet and vibrating member. Contact-piece or electrode *h* preferably has its free end bifurcated or hook-shaped to take about the free 85 end of electrode or contact-point *i*, as clearly shown in Figs. 1 and 2. The electrode *h*, it will be understood, is secured to the box *B*, which is made of wood or other non-conducting material, or to a wooden block 90 or other insulating material within the box, which may be located beneath the metallic casing *E* as clearly shown in Fig. 1. The contact-point *i* is pivotally secured at *k* to wall *E'* and takes over the top of gear *l* and 95 through the curved or eccentric slot *m* in wall *E* and between the bifurcated end of contact-piece *h*, as can clearly be seen in Figs. 3 and 4. Electrode *i* is preferably 100 made to bear frictionally against the wall *E* of slot *m* in any suitable manner, as for example by making electrode *i* in the nature of a spring-arm with the coil or twist therein as shown in Fig. 1 at *k'*, which tends to frictionally hold the free end of the electrode against the upper wall of the slot as clearly shown.

Suitably mounted between the walls *E* and *E'* of the metallic casing, on spindle *n*, is a gear *o*, which meshes with pinion *p* 105 mounted on spindle *q* on which is mounted gear *l*. Wound about spindle *n* and adjacent to gear *o* is a spring *r*, preferably of the clock-spring type, which exerts its tension on gear *o* so as to return it to its normal position. In order to keep the spring properly 110 in place, I provide disk *s*. Secured to gear

l and also connected with pinion *p*, is the drum or spool *t* on which is wound the string or wire *a*, Fig. 5, whose free end may be provided with a loop or hook to permit 5 of its being readily drawn out and secured at the desired point.

It is apparent from the foregoing that the tension of spring *r* tends, through the medium of gear *o* which meshes with pinion *p* 10 mounted on the spindle *q* on which the spool *t*, and gear *l* are secured, to wind up the string or wire *a* onto spool *t*, so that the moment the free end of the string or wire *a* is released or broken away from its fastening, 15 the gear *l* will be permitted to revolve in a direction that will take up the unwound portion of the wire or string. It is also apparent that the drawing out of string or wire *a* will compel the spool *t* and with it 20 spindle *q* and gear *l* to revolve in the opposite direction from that in which the tension of the spring exerts itself. The nature of slot *m* is such that when electrode *i* is moved toward the center of the slot, the electrode 25 will be made to take between the teeth of gear *l*. It is apparent therefore, that when the electrode *i* is thus set, a movement of gear *l* in either direction will also compel electrode *i* to move in the same direction until 30 the electrode reaches the ends of the slot *m* when it will be out of contact with gear *l*; and as the distance between the bifurcated end of electrode *h* is less than the length of slot *m*, the electrodes *i* and *h* will be brought 35 into contact with each other and the circuit closed.

The alarm is set by drawing out the string or wire *a* and fastening it across the path that will necessarily be taken or to the window or door, thereby also unwinding spring *r* and increasing its tension; when the string 40 has been fastened in place, the electrode *i* is moved into the center of slot *m*, bringing it into contact with the teeth of gear *l*. It is 45 evident, that if the string or wire *a* is drawn out farther, gear *l* will turn and move electrode *i* toward one end of slot *m* and into contact with one branch of stationary electrode *h*; while the release of string or wire 50 *a* will permit the tension of spring *r* to exert itself and turn gear *l* in the opposite direction and force electrode *i* from the center of slot *m* toward the other side of slot *m* and into contact with the other branch or bifurcation 55 of electrode *h*, thus, in either event, closing the circuit.

In order that the alarm may be "set" during absence, and at the same time permit of one string or wire answering for both 60 door and transom, I provide a tripping mechanism as illustrated in Fig. 5, which consists of rod *F*, the lower end of which is formed or provided with a rack as shown at *u*; while the upper end of the rod may be 65 bent to take over the casing intermediate of

the door-top and the transom, if the casing protrudes to any extent beyond the perpendicular plane of door and transom. The upper end of rod *F* is preferably provided with the hook-portion *u'*—see Fig. 6—which 70 is so formed as to present its points toward each other, leaving only a small distance between the tips as clearly shown in Fig. 6. When the alarm is "set" for the transom and door, the string or wire *a* is passed 75 through the hook or encircling portion *u'* as shown in Figs. 5 and 6. Secured onto the outside of the door is knob *G*, whose shank takes through the door and has its inner end provided with a pinion *v* which meshes with the rack *u* on rod *F*. The inner end of the shank of knob *G* may also be provided with a similar knob so that rod *F* can be operated and put into the desired position from the inside. 80

In order that the position of the hook-portion of the rod with reference to the string or wire *a* may be determined, dials *H*,—see Fig. 8—may be employed, provided with designations or degrees as indicated. 85 The relation between the dial and knob is such that when a predetermined point—or points—on the knob reaches a selected designation or degree on the dial, the hook-portion of the rod *F* will be in such position as 90 to permit of the opening of the door, allowing the string or wire to pass between the points of the hook, thereby leaving the string undisturbed.

It is apparent from the foregoing description, that when a party about to pass out of the door wishes to leave the alarm "set", the knob on the inside is turned until the selected points on knob and dial register, bringing the hook-portion into position to 10 permit it to pass the string *a* without interfering therewith and then after passing out and closing the door, the knob *G* on the outside is turned to throw the designated points out of register, thereby again bringing one 11 of the points into the horizontal plane of the string or wire *a*, as shown in Fig. 6.

It is apparent, that if the transom *A* is opened it will bend rod *F*,—which may be light or flexible—and pull on string or wire 1 *a* thereby operating the alarm; on the other hand, should the door *J* be opened, the string or wire *a* will be pulled by hook *u'* as previously described.

The lower portion of rod *F*, together with 1 pinion *v* may be covered by a plate as shown at *K*, Figs. 5 and 6.

When the mechanism is to be inclosed in a box *B* as shown in Fig. 1, it is advisable to provide the box with an opening as 1 shown at *L*, so that the alarm can be distinctly heard; and this opening may be covered with a screen or wire gauze so as to prevent anything getting into the box and interfering with the mechanism. Instead 1

however of placing all the mechanism in a box as shown, the electric door bell may be electrically connected with the "setting" mechanism which can be located at any convenient place.

It is clear the mechanism shown and described may be altered in certain details without departing from the spirit of my invention, and I do not wish to be understood 10 as limiting myself to the exact construction set forth.

It is also apparent that the device may be used as a fire alarm by arranging the lines, formed of any inflammable or fusible material, about a building, so that the moment 15 the spring-controlled mechanism is released, the alarm will be sounded.

Having thus shown and described what I believe to be the simplest form of my invention, what I claim and wish to secure by Letters Patent, is:—

1. A burglar alarm, comprising a casing one side whereof is provided with a slot, spring controlled gearing having an extended hub or spool mounted within said casing, an annunciator arranged in a normally open electric circuit, a spring controlled pivotally mounted electrode extending through the slot in said casing and arranged to have frictional contact with one side of the slot so as to maintain an adjusted position, said electrode being pressed into engagement with the spring controlled gearing when moved into its adjusted position, a stationary electrode whose free end extends about the pivoted electrode and out of contact therewith when the pivoted electrode is in its adjusted position, means secured to the extended hub or spool 40 and to be wound thereon, the other end of

said means being adapted to be secured at some distance from the hub or spool, so that when said means is moved the spring controlled gearing will rotate and move the pivoted electrode out of its adjusted position 45 and into contact with the stationary electrode.

2. A burglar alarm, comprising a casing provided with a transversely extending slot in one of its sides, the portion of the slot 50 intermediate of its ends extending into a lower horizontal plane than the ends, a spring controlled spool or drum mounted in said casing and having a serrated or toothed rim, an annunciator arranged in a normally open electric circuit, a pivotally mounted resilient electrode the end whereof extends through said slot and has frictional engagement with the upper side thereof, the pivotally mounted electrode being adapted to 60 be brought into engagement with the serrated or toothed rim when the outer end of the electrode is moved to a point intermediate of the ends of said slot, a stationary electrode having a bifurcated end extending to opposite sides of the pivoted electrode, and a cord or wire winding on said spool or drum, the one end of said cord or wire being adapted to be secured at a point removed from the alarm and revolving the 70 spool or drum against the action of the spring, so that when the cord or wire is interfered with the spool will revolve and move the pivotally mounted electrode into contact with the stationary electrode.

JOHN EMIL LILJEBLAD.
